J. W. SMITH

LATCH FOR GATES AND THE LIKE

Filed Oct. 15, 1923

Patented Nov. 16, 1926.

UNITED STATES PATENT OFFICE.

JOHN W. SMITH, OF DAYTON, OHIO.

LATCH FOR GATES AND THE LIKE.

Application filed October 15, 1923. Serial No. 668,512.

This invention relates to latches for gates and the like.

One object of the invention is to provide a strong durable latch which will be simple in its construction and which will not be easily broken or injured so as to render it inoperative.

A further object of the invention is to provide such a latch by means of which the adjacent edge of the gate will be held against vertical movement.

A further object of the invention is to provide such a latch which will prevent the adjacent edge of the gate from sagging.

15 A further object of the invention is to provide a latch mechanism comprising latching members spaced apart and controlled by the same operating member, so as to prevent the gate from being sprung, 20 or the lower corner thereof forced open without releasing the latch.

Other objects of the invention will appear as the device is described in detail.

In the accompanying drawings Fig. 1 is 25 a front elevation of a latch mechanism embodying my invention, with the connecting bar partly broken away; Fig. 2 is a side elevation of the invention, connected with the gate and gate post, which are partly 30 broken away; Fig. 3 is a vertical sectional view of the main latch taken on the line 3-3 of Fig. 1; Fig. 4 is a transverse sectional view taken on the line 4-4 of Fig. 1; Fig. 5 is a transverse sectional view taken 35 on the line 5-5 of Fig. 1; and Fig. 6 is a transverse sectional view taken on the line 6-6 of Fig. 1.

In these drawings I have illustrated one embodiment of my invention and have 40 shown the same as applied to a swinging gate and as comprising a plurality of latching devices. It will be understood, however, that this particular embodiment has been chosen for the purpose of illustration 45 only and that the latch may consist of one or more latching devices and may be applied to gates or other closures of various kinds and, further, that the mechanism may take various forms without departing from 50 the spirit of the invention.

In that particular embodiment of the invention here shown the main latching mechanism comprises an abutment 1 which is supported by the gate post 2 and which, in 55 the present instance, is rigidly secured to

and preferably formed integral with a supporting member or plate 3 which is rigidly attached to the post by suitable fastening devices, such as bolts 4 extending through apertured lugs 5 carried by the 60 supporting plate. This abutment 1 is adapted to engage the lower edge of a projection or lug 6 which is carried by the adjacent edge of the gate or closure 7, and to thereby support the adjacent edge of the 65 gate and prevent the same from sagging. The projection or lug 6 may take various forms but, as here shown, it is in the form of a vertical web rigidly secured to, and preferably formed integral with, a base 70 plate 6^a which is rigidly attached to the edge of the gate by suitable attaching devices, such as screws 8. The web may be reinforced by horizontal bracing members 75 or gussets 9 formed integral therewith so as to provide a very strong lug which will 80 will not be liable to damage even though roughly used. In order that this lug or projection 6 may be guided into proper contact with the abutment 1, in the event it 85 is not supported in alignment therewith, the abutment is provided with laterally projecting inclined portions 10 which provide beveled surfaces with which the lug may 90 contact as the gate is moved toward its closed position and which will tend to move the lug and the adjacent portion of the gate upwardly to a proper position with 95 relation to the abutment 1, thereby not only holding the gate against sagging but also properly positioning the lug for engagement by the latching member.

The latching member may take various forms but it is preferably mounted above the position occupied by the lug 6 when the gate is closed and is movable vertically into and out of locking engagement with that lug. In the present construction the latching member or keeper, which is shown at 11, is arranged in front of the supporting structure 3 and is slidably mounted for vertical movement thereon. To this end the latching member is carried by a plate 12 which is slidably mounted in suitable bearings on the supporting structure 3. The latching member 11 may be secured to this slideable plate in any suitable manner but is preferably formed integral therewith. The slideable member is mounted in a lower bearing 13 100 which is secured to the supporting structure 105 110 which is secured to the supporting structure

by suitable fastening devices, such as screws 14, and an upper bearing 15 which is formed integral with the supporting structure and is here shown in the form of a flange depending from a transverse portion or cap 16 at the upper end of the structure 3. The 5 slidable plate 12 which carries the latching member 11 has its upper portion curved outwardly so that it is substantially semi-circular in cross section, as shown at 17, and this portion of the plate constitutes a housing the edges of which are mounted in guideways 18 in the supporting structure 3 and the curved surface of which fits snugly 10 in the bearings 13 and 15. Ordinarily it is not desirable to make the latching member of sufficient weight to cause it to act quickly by gravity and I prefer to provide a yieldable member which will act upon the latching 15 member to move the same downwardly and hold the same in latching contact with the lug 6. In the present construction this yieldable member is in the form of a coiled spring 19 mounted within the housing 17 20 and confined between a lug 20 upon the bottom wall of said housing and a part carried by the supporting structure 3. In order that the tension of the spring may be adjustable I have here shown the upper end of the same 25 as contacting with a head 21 carried by the lower end of a rod 22 which is screw threaded into a boss 23 carried by the cap 16. A lock nut 24 is provided to retain the rod in its adjusted positions. In order that the 30 latching member 11 may be forced upwardly by the lug 6 to permit the latter to move into proper position beneath the same I have provided the latching member with laterally extending portions 25 the lower edges of 35 which are inclined to provide beveled contact surfaces for the lug. The latching member 11 is here shown as provided at its lower edge with a recess or notch 26 adapted to receive the upper edge of the lug 6. As the 40 gate is moved to its closed position the lower edge of the lug 6 will engage the beveled end of the abutment and as its movement continues the upper edge will engage the beveled projection of the adjacent side of the 45 latching member, thereby forcing that member upwardly against the action of the spring 19 and causing the lug to be moved onto the abutment 1 and into line with the recess 26 in the latching member. As soon 50 as the lug is in line with the recess the spring will force the latching member downwardly and cause it to embrace the lug, thereby holding the same firmly against displacement. The lower bearing 13 is provided 55 with two downwardly extending lugs 27 which are preferably formed integral with the bearing and which extend in the rear of the lateral projections 25 of the latching member and engage the respective sides of 60 that member in the rear of said projections. 65

In this manner the lugs 27 serve to brace the slidable latch against lateral displacement and also to reinforce the lateral projections 25 so as to prevent the same from being injured by a rearward pressure or blow. The lugs 27 and lateral projections 25 may also be utilized for locking the latching member in its closed position and, as here shown, these parts are provided with apertures 28 and 29 which will register one with the other when the latching member is in its lowermost or operative position, thereby permitting the insertion of a suitable locking member, such as a hasp of a pad lock 30. It will be noted that there is a lug 27 and a projection 25 on each side of the latch so that the latter may be locked from either side of the gate. Suitable means are provided for moving the latching member upwardly against the tension of the spring 19 to release the gate. This member may take various forms but, as here shown, comprises a lever 31 pivotally mounted between lugs 32 carried by the supporting structure 3 and extending rearwardly therefrom. The inner end of this lever is rounded, as shown at 33, and arranged to engage the lower surface of the lug 20 so that the movement of the lever about its axis will impart upward movement to that lug and consequently to the latching member with which the lug is connected. The outer portion of the lever extends through an opening 34 in the fence post and projects beyond the post far enough to provide for the convenient manipulation thereof.

A latch of this kind is usually arranged at a convenient height for manipulation and this requires that it be placed some distance above the lower edge of the gate. As a result it is sometimes possible, even when the gate is latched, to force the lower edge of the same inwardly past the fence post, thereby permitting the passage of small animals, such as pigs. In order to prevent twisting or swinging of the gate into a partially open position I prefer to provide two latching devices which will be spaced some distance apart so that when both are in operative positions the gate will be held against all twisting movement and cannot be sprung out of line with the fence post. To this end I have shown in the present drawings a second latch mounted on the post 2 some distance below the above described latch and preferably at a point spaced a comparatively short distance above the lower edge of the gate. As here shown, this second latch comprises a supporting member or plate 35 adapted to be rigidly secured by means of bolts 36, or otherwise, to the post 2. This plate is provided with a forwardly extending projection 37 the lateral portions of which are bent upwardly, as shown at 38, to provide 120 125 130

beveled contact surfaces. This projection 37 has an opening 39 formed therein and in this opening is mounted the latch member 40, this latch member being provided with 5 a recess 41 to receive the upper edge of a lug 42, which may be similar to the lug 6 and may be attached to the gate 7 in the same manner. The lateral portions of the latching member 40 are rounded or beveled, 10 as shown at 43, to enable the latch to be moved upwardly by contact with the lug 42, thereby permitting the lug to be moved into line with the recess 41. The latching member is slidably mounted on the supporting 15 plate 35 and to this end it is rigidly secured to and formed integral with a vertically arranged guide bar 44 which is slidably mounted in a guideway 45 formed in the plate 35. A bearing 46 embraces the upper 20 portion of the guide member or bar 44 and cooperates with the projection 37 to retain the latch in its proper position with relation to the supporting member. The latching member 40 is yieldably held in its lower- 25 most position but, in the present instance, I have not provided this lower latch with separate means either for yieldably holding the same in its lower position or for moving the same into its inoperative position 30 against the action of such yieldable means, but have so connected the lower latching member with the upper latching member that the lower latching member will be acted upon by the spring 19 and by the 35 operating device or lever 31, thereby enabling the two latching members to be moved simultaneously into and out of their operative positions. In the present construction I have connected the guide mem- 40 ber or plate 44 of the lower latching member with the slideable plate 12 of the upper latching member by means of a bar 47. The length of this bar may be varied so as to permit the two latching devices to be spaced 45 apart any desired distance without interfering with the manipulation of the lower latching device by means of the operating lever for the upper latching device. As a rule it is not necessary to provide the lower 50 latching member with a supporting abut- ment for the lug 42 as the gate will be adequately supported by the upper abut- ment, but obviously such an abutment could be provided in connection with the lower 55 latching device, if desired.

The operation of the device will be readily understood from the foregoing description and it will be apparent that I have provided a latch for gates, or other movable 60 closures, which is of a very strong durable character, will act quickly and positively to secure the gate when it has been moved to its closed position; which will support the edge of the gate against any tendency 65 to sag; and which cannot be released by an

upward thrust on the gate but will serve to limit that upward thrust to such an extent that it will be immaterial, the upward thrust of the gate being limited in the present instance to the amount of vertical move- 70 ment of which the latching member is capable. Further, the gate is normally locked against movement in either direction but may be swung open in either direction by releasing the latch. It will also be apparent that I have provided latching mechanism by means of which the gate may be secured at two separate points, thereby preventing the same from being twisted or sprung into a partially open position and that this latch- 75 ing mechanism is operable by a single actuating device so that the gate may be simultaneously released at both points. When the lower latching mechanism is employed the projection 37, which lies in the path of 80 the lug 42, will positively prevent the upward movement of the lug of the gate.

While I have shown and described one embodiment of my invention, I wish it to be understood that I do not desire to be limited to the details thereof as various modifications may appear to a person skilled in the art.

Having now fully described my invention, what I claim as new and desire to secure by Letters Patent, is:

1. A latch for a gate or the like comprising a supporting plate having an abutment near the lower end thereof to engage and support a projection carried by the gate and having a bearing near the upper end thereof, a plate slidably mounted in said bearing and having a hollow portion forming a housing, a latching member carried by said slide- 100 able plate, having a recess in the lower edge thereof to receive the projection on said gate and having its lateral portions inclined to form contact surfaces, a spring arranged in said housing and acting on said slide- 105 able plate to move said latching member downwardly, and an actuating device for moving said slideable plate and said latching member against the tension of said spring.

2. A latch for a gate or the like, comprising a supporting structure having an outwardly extending projection provided with a downwardly extending flange to form a bearing and also having a second bearing arranged below the first mentioned bearing, 115 a plate having a hollow portion slidably mounted in said bearings and having a part forming a bottom wall therefor, a screw threaded rod mounted in said projection, a head carried by said rod, a spring confined between said head and said bottom wall, a latching member carried by said plate, and means for moving said plate against the tension of said spring to move said latching member to an inoperative position.

3. A latch for a gate or the like com-

- prising a supporting structure having a vertical guideway and provided with bearings, a plate having a part curved about a longitudinal axis, mounted in said bearings and having its edges slidably mounted in said guideway, a latching member carried by said plate, a spring arranged within the curved portion of said plate and acting thereon to move said latching member to its operative position, and an actuating device for moving said plate against the tension of said spring to move said latching member into an inoperative position.
4. A latch for a gate or the like comprising a supporting structure, a plate slidably mounted on said structure and having a part forming a housing, a lug forming the bottom wall for said housing, a latching member carried by said plate, a spring arranged within said housing and confined between said lug and a part carried by said supporting structure, and a lever mounted adjacent to said housing and having a part adapted to engage said lug to impart movement to said latching member against the tension of said spring.
5. A latch for a gate or the like comprising a supporting structure, a plate slidably mounted on said supporting structure and having a part forming a housing, said housing having a bottom wall, the lower surface of which forms a shoulder, a latching member carried by said plate, a bearing carried by said supporting structure and extending about said housing, a part carried by the upper end of said supporting structure and having a depending flange to form a second bearing for said housing, a rod screw threaded into said supporting structure, a head carried by said rod, a coiled spring confined between said head and the bottom of said housing, and a lever having one end arranged to engage the shoulder formed beneath the bottom of said housing.
6. A latch for a gate or the like, comprising a supporting structure, a latching member slidably mounted on said supporting structure and having laterally extending portions provided with inclined lower edges, lugs rigidly secured to said supporting structure and arranged to respectively engage the rear surfaces of said lateral projections on the opposite sides of said latching member.
7. A latch for a gate or the like, comprising a supporting structure, a latching member slidably mounted on said supporting structure and having laterally extending portions provided with inclined lower edges, lugs rigidly secured to said supporting structure and arranged to respectively engage the opposite sides of said latching member in the rear of said projections to brace said member against lateral movement.
8. A latch for a gate or the like, comprising a supporting structure, a latching member slidably mounted on said supporting structure and having laterally extending portions provided with inclined lower edges, lugs rigidly secured to said supporting structure and arranged to respectively engage the opposite sides of said latching member in the rear of said projections to brace said member against lateral movement, and to engage the rear faces of said lateral projections to reinforce the same.
9. A latch for a gate or the like, comprising a supporting structure, a latching member slidably mounted on said supporting structure and having laterally extending portions provided with inclined lower edges, lugs rigidly secured to said supporting structure and arranged on the opposite sides of the rear portion of said latching member adjacent to said lateral projections, and means for locking the corresponding lugs and projections one to the other.
10. A latch for a gate or the like, comprising a supporting structure, a latching member slidably mounted on said supporting structure and having laterally extending portions provided with inclined lower edges, bracing lugs rigidly secured to said supporting structure and arranged on the opposite sides of the rear portion of said latching member adjacent to said lateral projections, said lugs and said projections on the respective sides of said latching member having openings adapted to register one with the other when said latching member is in its operative position and adapted to receive a locking device.
11. A latch for a gate or the like comprising a supporting structure, a plate slidably mounted on said structure, a latching member carried by said plate and having laterally extending projections, a bearing for said plate carried by said supporting structure and having lugs depending therefrom in the rear of said lateral projections and arranged on opposite sides of the rear portion of said latching member.
12. A latch for a gate or the like comprising a supporting structure, an abutment carried by said supporting structure, a plate slidably mounted on said supporting structure above said abutment, bearings for said plate, a latching member carried by said plate and having a recess in its lower edge arranged above said abutment, a spring tending to move said plate and said latching member toward said abutment, and means for moving said latching member away from said abutment against the tension of said spring.
13. In a latching mechanism for a gate or the like, a latching device comprising a latching member adapted to engage a projection carried by a gate, a second latching device spaced from the first mentioned latch-

ing device and comprising a latching member adapted to engage a second projection carried by said gate, means for rigidly connecting said latching members one to the other to cause them to move simultaneously in the same direction, and a device acting on one of said latching members to actuate both of them.

14. In a latching mechanism for a gate or the like, a latching device comprising a latching member adapted to engage a projection carried by a gate, yieldable means for holding said latching member normally in its operative position, a device for moving said latching member into its inoperative position, a second latching device spaced some distance from the first mentioned latching device and comprising a latching member adapted to engage a second projection carried by said gate, and means for connecting said second latching member with the first mentioned latching member to cause said second latching member to be moved by and in the same direction as the first mentioned latching member.

15. A latching mechanism for a gate or the like comprising a supporting structure, an abutment carried by said supporting structure to engage the lower edge of a projection carried by a gate, a latching member mounted on said supporting structure for vertical movement and having a recess to engage the upper edge of said projection, a spring acting on said latching member to hold the same normally in its operative position, an actuating device to move said latching member against the tension of said spring, a second supporting structure arranged below and spaced from the first mentioned supporting structure, a latching member slidably mounted on said second supporting structure and having a recess to engage the upper edge of a second projection carried by said gate, and a bar for rigidly connecting said latching members one to the other.

16. A latching mechanism for a gate or the like comprising a supporting structure, an abutment carried by said supporting structure to engage the lower edge of a projection carried by a gate, a latching member mounted on said supporting structure for vertical movement and having a recess to engage the upper edge of said projection, a spring acting on said latching member to hold the same normally in its operative position, an actuating device to move said latching member against the tension of said spring, a second supporting structure mounted below and spaced from the first mentioned supporting structure and having a vertical guideway, a guide member mounted

in said guideway, a latching member carried by said guide member and adapted to engage a second projection carried by said gate, and a bar connecting said guide member with the first mentioned latching member. 65

17. A latching mechanism for a gate or the like comprising a supporting plate provided with a transverse projection extending forwardly therefrom and having its lateral portions inclined to form contact surfaces, said projection having an opening adjacent to said supporting plate, a latching member slidably mounted on said supporting plate, arranged within the opening of said projection and having a recess to receive the projection carried by said plate, yieldable means for moving said latching member toward the projection on 80 said gate, and other means for moving the same from said projection.

18. A latching mechanism for a gate or the like, comprising a supporting structure provided with a forwardly extending projection having an opening adjacent to said supporting structure, said structure also having a longitudinal guideway communicating with said opening, a latching member arranged within the opening of said projection and having a part slidably mounted in said guideway, said latching member having a recess to receive a projection carried by the gate, yieldable means for moving said latching member toward said projection, and other means for moving the same from said projection. 95

19. A latching mechanism for a gate or the like, comprising a supporting structure, an abutment carried by said structure and arranged to engage and support a projection carried by the gate, a latching member mounted on said supporting structure for movement toward and from said abutment and having a part to engage said projection and hold said gate against movement, a second supporting structure provided with a forwardly extending projection having an opening adjacent to said second supporting structure and provided with a longitudinal guideway adjacent to said opening, a second latching member arranged within the opening in said projection and having a part slidably mounted in said guideway and also having a part to engage a second projection on said gate, yieldable means for moving said latching members toward the respective projections on said gate, and other means for moving the same from said projections. 110

In testimony whereof, I affix my signature hereto.

JOHN W. SMITH.
